UNITED STATES PATENT OFFICE.

STEPHEN J. KUBEL, OF WASHINGTON, DISTRICT OF COLUMBIA.

PAPER-FEED GAGE.

1,189,264.

Specification of Letters Patent.

Patented July 4, 1916.

Application filed November 27, 1915. Serial No. 63,892.

To all whom it may concern:

Be it known that I, STEPHEN J. KUBEL, a citizen of the United States, residing in the city of Washington, District of Columbia, have invented certain new and useful 5 Improvements in Paper-Feed Gages; and I do hereby declare the following to be a full, clear, and exact description of the invention, such as will enable others skilled 10 in the art to which it appertains to make and use the same.

The invention relates to gages for machines involving mechanism for operation upon sheets or webs of paper and other material, and has for its object to provide a 15 novel form of sheet gage, with electrical actuating means which may be operated to adjust the gage either from a point immediately adjacent the gage or from some remote point, as for example, the usual position or station of the operator in charge of 20 the apparatus. Gages of this character are extensively employed in printing presses, but their application is also general to other 25 machines involving the feed of sheets or webs, and it is to be understood that the present invention is applicable to gages of this character generally.

The invention is illustrated in the accompanying drawings in which,

Figure 1 is a diagrammatic side elevation of a printing press having gages applied thereto. Fig. 2 is an enlarged fragmentary perspective of the apparatus shown 35 in Fig. 1, indicating the application of the invention as end gages and a side gage. Fig. 3 is an enlarged side elevation, partly in section, of one of the gages. Fig. 4 is a vertical transverse section of the gage on line 4—4 of Fig. 3. Fig. 5 is a sectional 40 plan on line 5—5 of Fig. 3. Fig. 6 is a detail, partly in section, of the locking mechanism for the gage. Fig. 7 is a plan view, partly in section, of the lower portions of 45 the solenoid cores. Fig. 8 is a detailed perspective of one of the solenoid cores. Fig. 9 is a diagram of the circuits for operating the electromagnetic actuators and lock for a given gage.

50 Referring to the drawings, which illustrate a rotary cylinder printing press, but merely by way of example of the application of the present invention, A indicates such a press, having the usual cylinder B such a press, having the usual cylinder B 55 and feed board C. Adjustably mounted on

the feed board C is a side gage G' involving the invention hereinafter to be more particularly described. Mounted upon the usual rock shaft E are two front gages G, G, 60 also involving the principles of construction and operation which characterize the present invention.

The means for adjusting and operating the front and side gages G, G' respectively are practically identical and a description of these means in connection with the front gage will also serve in respect of the side gage and gages for other purposes in machines involving the feeding of sheets or webs of paper and the like.

Each of the front gages involves an annular bracket piece 2 adapted to be secured by the usual form of clamp 6, to the rock shaft E. Slidably mounted on the horizontal member of the bracket 2 is a gage arm 1, which is locked to the bracket 2 by means of a set screw 4 carried by the bracket and engaging a slot 3 in the gage arm 1. The rear portion of the gage arm 1 is provided with an angular offset, in which 75 is journaled a set screw 5, which engages a threaded opening in the bracket 2, and by means of which the ordinary coarse or rough adjustments of the gage may be effected, as will be understood.

The forward end of the gage arm 1 is provided with a downward angular extension 10, adjacent to which and secured to the under face of the arm 1 is a U-shaped frame or yoke 11. In the latter, there is 80 journaled a gage spindle 12 capable of rotary movement, but held against longitudinal movement by suitable collars engaging the exterior faces of the yoke or frame 11. The forward end of said spindle 12 is provided 85 with a screw thread 13 and upon this screw-threaded portion of said spindle is mounted a threaded yoke 14 provided with forwardly extending pins 15 to the outer end of which is secured gage plate 16, which 90 latter is provided with the usual spring guard 17. It will be understood, of course, that as the spindle 12 is rotated in one direction or the other, the gage plate 16 will 95 be moved toward and from the vertical 100 member 10 of the gage arm, and as it is proposed to operate the spindle 12 by a step by step movement, it will be apparent that exceedingly close and fine adjustments 105 of the gage plate 16 may be effected.

Secured to the spindle 12 is a sleeve-like member having two ratchet rims 20 and 21 thereon, between which is located a locking ratchet member 22 provided with a series of peripheral openings, more particularly illustrated in Figs. 5 and 6. The ratchet members 20 and 21 are oppositely disposed so that when they are separately actuated, the spindle will be rotated step by step in a clockwise or an anti-clockwise direction, depending upon which of the ratchets is actuated.

The operating means for the ratchets 20 and 21 consists of a novel form of electro-magnetic motor, consisting of two pairs of solenoids, 25, 26 and 25^a, 26^a respectively. As these solenoids and their appurtenances are practically duplicates, it will be necessary to describe in detail one pair only. The pairs of solenoids are mounted on the under face of the gage arm 1 and within the yoke or frame 11, as shown in Figs. 3 and 4. Reciprocably mounted in the coil of solenoid member 25 is a core 27 provided with an angularly disposed lower end 27', which is provided with a rigid pawl member 29, adapted to be thrown into operative engagement with ratchet member 20. The corresponding solenoid core 27^a on the opposite side of the spindle 12 is provided with a similar pawl or detent 29', which co-operates with ratchet member 21. The solenoid member 26 is provided with a reciprocating core 28, the lower end of which is recessed to receive the forward end of core section 27', when the solenoid members are energized. Normally, the core sections 27' and 28 are held apart, so as to disengage pawl 29 from ratchet 20, by means of a helical spring 31, mounted upon a pin 30, secured to core 28 and projecting through an opening 32 in the end of core section 27', as particularly illustrated in Fig. 7. This relation of the core members 27 and 28 maintains the pawl 29 out of engagement with corresponding ratchet 20. When, however, the solenoid members 25 and 26 are energized, the core members 27 and 28 are immediately magnetized so that the lower angular member 27' of core 27 is attracted to and held by the lower end of core 28, against the tension of spring 31, thereby bringing pawl 29 into engaging relation with ratchet 20. Practically simultaneously, or at least, but a short interval after this operation, both cores 27 and 28 are lifted by their respective solenoid coils so that the pawl 29 turns the ratchet 20 and with it the spindle 12, one step, equal to the upward movement of the solenoid cores, which is substantially equivalent to the rotary advancement of the ratchet 20 and the spindle 12 a distance equal to one ratchet tooth. It will be understood that inasmuch as the opposite pair of solenoids

25^a and 26^a operate similarly, they will move the ratchet 21 and spindle 12 in an opposite direction, incrementally, and equal to one ratchet tooth for each operation of the solenoids 25^a and 26^a.

Mounted centrally of the solenoid members 25 and 26, and 25^a and 26^a is a further solenoid 35, having a core 36, the lower end of which is provided with a stop or detent 37 adapted to engage and co-operate with the peripheral openings in the lock member 22, located between the ratchets 20 and 21 on the spindle 12. Normally, the solenoid core 36 is in its lower or locking position, with the end 37 thereof engaging the subjacent recess in the locking member 22, as shown in Fig. 6, thereby holding the spindle 12 and gage plate 16 rigid and immovable, even when the gage is subject to the jars and shocks of operation, or even bodily movement, as is the case in certain types of presses. When, however, the solenoid 35 is energized, its core 36 is retracted, releasing the spindle 12 and permitting the same to be rotated in either direction to effect the finer and accurate adjustments of the gage plate 16. As indicated, the adjustment of the spindle 12 and gage plate 16 is effected by the respective sets of solenoids 25, 26 and 25^a, 26^a.

In order to energize the respective solenoids of a given gage, these solenoids are connected in circuit with a source of electric energy Y, see Fig. 9, which circuits are controlled by push buttons or circuit closers, one set of circuit closers being located preferably on or adjacent to the gage proper, and the other set of circuit closers being located on the machine to which the gage is applied and in a position to be reached by the operator of the machine without the latter leaving his position, such position being, in the machine illustrated, the delivery end of the press A, where the operator can watch the sheets as they are delivered and determine instantly whether the gages are properly set. The circuit closing elements preferably consist of push buttons p and p', which are located at the point of distant control, and push buttons p^a and p^b, which are preferably attached to the gage arm 1 adjacent to the solenoids, as indicated in Figs. 3 and 4. Suitable cables or conductors X serve to establish connection between the source of electric energy Y and the solenoids 25, 26 and 25^a, 26^a and solenoid 35, when the corresponding push buttons or circuit closers p, p', p^a, and p^b are operated, as will be understood from the wiring diagram shown in Fig. 9, which represents the electromagnetic actuating and locking means for a single gage. It will be noted that the solenoid 35 is so connected with the energizing circuit that it is included in circuit with either set of the operating sole-

noids 25, 26 and 25^a, 26^a, whenever one or the other of said sets is energized by the operation of one or the other of the push buttons controlling the respective solenoid sets, thereby insuring the unlocking of the ratchet mechanism carried by spindle 12 before the energized solenoid set operates to turn the spindle.

Inasmuch as it is customary to use two or more gages on a given machine, it will be found convenient to arrange the push buttons or circuit closing devices for the distant control of all the gages, in a single bank or block, as illustrated at P in Fig. 1, and connecting the appropriate push buttons to the corresponding solenoids of the various gages, as will be understood.

With the apparatus, as described, installed, say, for example, on a printing press, as illustrated in Fig. 1, when it is desired to adjust one of the front gages, G, for example the left hand gage shown in Fig. 2, such adjustment may be effected either immediately at the gage by operating the proper push button p^a or p^b , or by operating one of the corresponding buttons p or p' in the bank of buttons P at the discharge end of the press. If, for example, the operator observes that the left hand gage G requires to be advanced slightly, without leaving his position, he presses the appropriate button p in the bank P and thereby energizes the solenoid members 25, 26 and solenoid 35, which unlocks spindle 12 and rotates the same one step. If this extent of adjustment is not sufficient, the actuation of push button p is repeated until the desired adjustment is obtained. Instead of effecting the adjustment from the point of distant control, the operator may adjust the gage by means of the push button p^a located on the top of the arm 1 and adjacent to the coöperating set of solenoids.

Obviously, the invention may be applied to any of the well known types of gages and may, as a matter of fact, be substituted for the various gages now employed in machines involving a feed of sheets or webs of various materials.

50 What I claim is:—

1. A feed gage comprising a support, a rotary screw-threaded spindle carried thereby, a gage plate adjustably connected with the threaded end of said spindle, electromagnets for actuating the spindle in either direction, operating circuits for said magnets, a detent for locking said spindle, and electromagnetic means for disengaging the detent and spindle when the circuit to either

electromagnet is energized to actuate the 60 spindle.

2. A feed gage comprising a support, a rotary spindle, a gage plate operatively connected with said spindle, electromagnets for actuating said spindle in either direction, 65 operating circuits for said magnets, a detent for locking said spindle, and electromagnetic means for disengaging the detent and spindle when the circuit to either electromagnet is energized to actuate the spindle. 70

3. A feed gage comprising a gage device, electromagnetic means for operating the same step by step in either direction, means for locking the gage at the end of each step, and electromagnetic means energized 75 simultaneously with either operating means for releasing the locking means.

4. A feed gage comprising a rotary spindle, a gage plate operatively connected therewith, actuating and locking ratchets on 80 said spindle, solenoids for operating said actuating ratchets step by step in either direction, a detent engaging the locking ratchet at the end of each step, and an electromagnet energized simultaneously with either operating solenoid for retracting said detent. 85

5. A feed gage comprising a gage device, electromagnetic means for operating the same step by step in either direction, circuits for said electromagnetic operating 90 means, and circuit closing means carried by the gage and located at some distant point of control respectively for closing the circuit for energizing said electromagnetic operating means.

6. A feed gage comprising a gage plate, a rotary spindle for adjusting the plate, oppositely disposed ratchets on said spindle, and electromagnetic means for operating said ratchets, each of said operating means, 100 comprising a double solenoid, separate cores for the solenoid members, one of said cores having an angularly disposed lower section adapted to be attracted by the other core, when the solenoid is energized, and a pawl 105 on said angularly disposed member coöperating with the corresponding ratchet.

7. An actuator comprising a ratchet for adjusting the gage, a double solenoid, separate cores for each solenoid member, one of 110 said cores having an angularly disposed lower section adapted to be attracted by the other core when the solenoid is energized, and a pawl on said angularly disposed member for operating said ratchet when the 115 cores are attracted.

In testimony whereof I affix my signature
STEPHEN J. KUBEL. [L. s.]
